WELT SHOE PRESS

William Carpenter Card, Jr., Winthrop, Mass., assignor to Compo Shoe Machinery Corporation, Boston, Mass., a corporation of Delaware

Application March 10, 1944, Serial No. 525,912

37 Claims. (Cl. 12—33)

This invention relates to sole pressing apparatus and relates more particularly to a press for use in the manufacture of welted footwear wherein outsoles are adhesively attached to a welt secured to the shoe bottom.

In attaching a sole to a shoe having a welt extension, it is necessary to support the welt, at least around the forepart and outside shank portions of the shoe; to prevent bending of the welt under the influence of the sole attaching pressure; to ensure that the welt is in intimate contact with the sole, and that they are held together with sufficient pressure to obtain a good adhesive bond. Prior sole attaching devices have provided welt supports, but such supports have, however, simply been additions to conventional forms of presses and as they are located above the sole pressing pad they interfere with an operator's vision; thus making it extremely difficult to see that the shoe is properly located with respect to the sole pressing pad and, that the welt support is in proper engaging relation with the welt crease of the shoe.

Such previous welt supports have also been difficult to adjust to the size and shape of the shoe being processed and generally, attempts to provide simpler adjustments have so encumbered the press that placement of a shoe is made a slow and painstaking operation.

The present invention provides an improved sole attaching press having as one feature, a novel form of welt support which is adapted to enter the welt crease of a shoe placed thereon while allowing adequate visibility of the complete shoe bottom.

Another feature is the provision of efficient mechanism for adjusting the welt support to conform to the shape and size of the shoe being operated upon and which does not interfere with an operator's vision or restrict easy placement of a shoe into the press.

Other features of the invention are the provision of simple and efficient mechanisms which allow a shoe to be placed upon the welt support in an inverted position while the sole pressing pad is in a remote position; pressure resisting members to be brought into proper engagement with the shoe and its last regardless of size or shape; the welt support to be conformed to the shape and size of the shoe being operated upon, and a sole pressing pad to be brought into pressing engagement with the shoe.

Another feature is the provision of a single control for adjustment of the welt support to the length and width of the shoe and for properly

spacing the shoe contacting pressure resisting members.

Still another feature is the provision of a single control for allowing the shoe contacting pressure resisting members to move to or away from the shoe; for locking them in position and for conforming a portion of the welt support to the shape of the shoe.

An object of this invention is to speed up the production of cemented welt shoes by providing improved apparatus of simple construction which can be used effectively and efficiently to adhesively attach the outsoles thereto.

Another object of the invention is to provide apparatus for use in attaching soles to welted shoes of various shapes and sizes and which will give uniform results, high production and ease of operation.

A further object of the invention is to provide an improved welt support which is rigid enough to resist the sole attaching pressure and yet which has the flexibility to allow it to curve in two planes so that it may be adjusted to accommodate a complete range of shoe sizes.

Other features and objects of the invention will in part be obvious and will in part appear hereinafter. The invention accordingly comprises the features of construction, combination of elements, and arrangements of parts which will be exemplified in the construction herein-after set forth and the scope of the application of which will be indicated in the claims.

For a fuller understanding of the nature and objects of the invention, reference should be had to the following detailed description taken in connection with the accompanying drawings, in which:

Fig. 1 is a right side elevation of a shoe press embodying features of the invention, and showing the parts in operative position with a shoe;

Fig. 2 is a plan view of the shoe press shown in Fig. 1;

Fig. 3 is a sectional plan view taken substantially along lines 3—3 of Fig. 1, and showing the welt support cover removed and the shoe removed;

Fig. 4 is a front elevation, the welt support cover being in section, and other portions of the press being broken away;

Fig. 5 is a sectional plan view taken substantially along lines 5—5 of Fig. 1;

Fig. 6 is a partial front elevation similar to Fig. 4 but showing a shoe in position upon the welt support;

Fig. 7 is a sectional view on an enlarged scale showing the welt support construction;

Fig. 8 is a partial left side elevation partially in section and showing the sole pressing pad in pressing relation with a shoe;

Fig. 9 is a fragmentary sectional view taken substantially along lines 9—9 of Fig. 8 showing the welt support urged into relation with the outside shank portion of a shoe;

Fig. 10 is similar to Fig. 9 but showing the position of the welt support and other parts prior to movement of the control handle;

Fig. 11 is a fragmentary sectional view taken substantially along lines 11—11 of Fig. 6; and

Fig. 12 is a plan view similar to Fig. 3 but showing a shoe in position upon the welt support.

The press as illustrated by the drawings is for a right foot shoe and except for mere reversal of parts and/or shapes, the left foot press is of the same construction.

Referring now to Figs. 1 and 2, each press comprises a base 15 which may be secured by the screws 16 to a conventional carrier such as a turret or conveyor (not shown). The base 15 is provided with bosses 17 having bores, through which pass the reduced diameters 18 of the vertical upstanding rods 19. The nuts 20 firmly clamp the rods to the base.

The upper ends of the rods 19 also have a reduced diameter 21 which passes through bores formed in a welt support platen 22 which is firmly secured to the rods 19 by the nuts 23.

The welt support platen 22 has an internal configuration 24 somewhat like a shoe but somewhat larger than the largest shoe to be processed and it extends around a shoe from approximately the inside ball point entirely around the forepart portion and as far as the outside heel breast line. The upper surface of the platen is provided with a face 25 which is curved at the shank portion to substantially correspond with the shank curvature of the shoes to be processed, and upon which rests a welt support 26.

The welt support 26, which is best shown in Figs. 3 and 7 comprises a series of rigid finger like members 30, which may be of square or other rectangular cross section, each having its inner or shoe engaging end beveled slightly on its upper surface at 31, and more acutely beveled on its under surface 32, so as to enable them to fit in the welt crease of a shoe. Each finger member is provided with a hole 33 which serves as an anchorage for a strip 34 of rubber or other flexible and resilient material which may be moulded to the fingers or otherwise secured thereto. It is preferable to mould the rubber strip 34 to the fingers while they are fanned out to form a U shape so that only a slight flexing of the strip will conform it to the shape of a shoe. However, the strip 34 may be secured to the fingers while they are in a continuous row, and flexing of the strip will then allow the fingers to fan out and form the U shape.

It can readily be seen that a welt support constructed in the above manner may be flexed in two or more planes to allow it to assume the same shape as a shoe and that as the finger members 30 are rigid they are supported by the upper face 25 of the platen 22 so that considerable pressure can be applied to their outer ends without causing permanent distortion. It can also be seen that the continuous rubber strip 34 forms an even and continuous resilient face

against which a welt may be pressed without marking or otherwise marring its finish.

The welt support 26 has sufficient length to allow it to surround the largest size shoe to be processed, from the inside ball point to the outside heel breast line, and suitable means for varying the effective length of the welt support for operating upon smaller shoes, is provided. The welt support 26 is secured at its end 35 to a laterally slidabie block 36 by the screws 37, and this end of the welt support is prevented from movement longitudinally of a shoe and defines the inside ball point of all shoes to be processed. The other end 38 of the welt support is secured by the screws 39 to a cylinder or drum 40 keyed to a shaft 41 journalled in a bearing 42 depending from the welt support platen 22. A hand wheel 43 is keyed to the other end of the shaft 41, and rotation of the hand wheel in a clockwise direction as viewed in Fig. 8, also rotates the drum 40, causing the welt support 26 to be wrapped around it to shorten its effective length. Reverse rotation of the hand wheel increases its effective length.

As shown in Figs. 11 and 12, an index pointer 44 is attached to the side of the welt support platen 22 to register with size markings on a cam piece 45 forming a part of and rotatable with the hand wheel 43. This index allows an operator to adjust the effective length of the welt support according to the size of the shoe to be operated upon.

The welt support platen 22 has a relieved portion 46 which is below the welt finger surface 25, and the fingers 30 around the toe and inside forepart engaging portions are provided with pins 47 which depend below the fingers and engage against the shoulder formed between the surface 25 and the relieved portion 46, to act as stops to prevent the welt support from being withdrawn too far as it is adjusted for size.

To keep the welt support in contact with the surface 25 at all times and to prevent tipping of the welt support fingers when pressure is applied thereto, the platen 22 is provided with an upstanding marginal wall 48 which extends above the surface 25 a few thousandths of an inch higher than the thickness of the welt support fingers, and a cover 49, having an internal shape somewhat larger than a shoe, is secured by the screws 50 to the marginal wall 48.

As the welt support length is altered to accommodate smaller size shoes, the fingers 30 around the toe and inside forepart portions are withdrawn from their support between the cover 49 and the platen surface 25. Therefore, the fingers at these portions are made longer to ensure that they have adequate support to resist the sole attaching press.

It is desirable to apply pressure to the complete sole area of a shoe, and at the inside ball portion it is desirable to exert sufficient pressure to wrap the welt and outsole tightly up against the shoe upper. In order to resist these pressures, shoe supporting members are provided which are arranged to contact the shoe and last after the shoe has been positioned upon the welt support. As best shown in Fig. 1 and Fig. 11, a bracket 51 is secured by screws 52 to the base 15 and is provided with a vertical slot 53 in which a heel support post 54 is slidably supported. The upper end of the post 54 has pivoted thereto at 55, a last contacting plate 56 which by virtue of its pivot can adapt itself to the angle formed by the cone of a last. The

post 54 is bored at its lower end to receive a spring 57 which gives the post a normal bias upwards.

A longitudinally movable bracket 60 which is held to ways 61 formed on the base 15 by the gib 62 is also provided with a vertical slot 63 in which is slidably mounted a toe support post 84 having pivoted at 65 to its upper end, a toe support pad 66. The lower end of the post 64 is provided with a bore to receive a spring 67 which serves to give the post a normally upward bias.

The support posts 54 and 64 have ratchet teeth cut on one side thereof and each bracket has formed thereon a bearing supporting a shaft 68 to which is keyed a pawl 69. Another pawl 70 is freely mounted upon each shaft. The pawls have extensions 71 which are adapted to be engaged by the spring 72 held in bosses 73 formed on the brackets 51 and 60 to give the pawls bias towards the ratchet teeth formed on the posts. The bosses 73 are threaded to receive the screws 74 which serve to adjust the tension of the springs biasing the pawls towards engagement with the ratchet teeth of the posts.

While placing a shoe upon the welt support of the press, the toe and heel supports are kept in a lowered position so that they do not contact the shoe, and this is accomplished by providing the posts 54 and 64 with a roll 75 extending through a slot in the side of the brackets 51 and 60. A cam bar 80 is slidably mounted in a slot 81 formed in a bracket 82 extending upward from the base 15 and is held in place by the gib 83. This cam bar is provided with a handle 84 which allows it to be moved towards and away from the operator thereof and when it is moved towards the forward position as shown in Fig. 11, the cams 85 contact the rolls 75 and press the posts 54 and 64 downwardly against the pressure of the springs 57 and 67.

The upper side of the cam bar 80 is provided with the cam surfaces 86 which contact the rolls 87 secured to the arms 88 keyed to the pawl shafts 68, to lift the pawls 69 out of engagement with the ratchet teeth on the posts 64 and 54.

The pawls 70 which are free upon the shafts 68 are made one half of the ratchet teeth pitch longer than the pawls 69 so that the posts 54 and 74 may be locked in position without undue lost motion and also so that the ratchet teeth can be made strong enough to withstand the pressure applied thereto.

To lift the pawls 70 out of engagement with the ratchet teeth, a finger 89 is secured to each of the pawls 69 to contact the extension 71 of the pawls 70.

To properly space the toe and heel supporting members 56 and 66 according to the shoe size to be inserted into the press, the bracket 60 as previously described, is movable along the ways 61, and movement of this bracket 60 is accomplished simultaneously with the adjusting of the welt support. To accomplish this, a cam plate 45 is formed on the hand wheel 43 and has cut therein a cam slot 90 which engages with a roll 91 secured to an arm 92 of a lever 93, pivoted at 94, to a stationary support 95 held on the rods 19. The other arm 96 of the lever is connected by a clevis pin 97 to one end of a link 98, and the other end of the link is pivoted at 99 to the bracket 60.

Thus, as the hand wheel 43 is rotated in a clockwise direction as viewed in Fig. 8 to adjust

the welt support for a smaller shoe, the bracket 60 carrying the toe support pad 66 is moved closer towards the heel support. Fig. 11 illustrates the mechanism with the welt support adjusted for the smallest shoe and the toe support brought to its correct position for such shoe, while Fig. 8 shows the mechanism adjustment for the largest size shoes.

As the hand wheel 43 is adjusted to set the 10 welt support to size and to space the toe support 66, the inside ball portion of the welt support is also regulated according to the shoe size to be processed, by means of a cam 100 which is secured to the bracket 60 by the screws 101 so that it moves with the bracket 60. A bell crank 102 is pivoted at 103 to a bracket 104 secured by the screws 105 to the press base 15, and the short arm 106 of the bell crank lever carries a spherical roll 107 which engages with the cam 100. The long arm 108 of the bell crank lever has a pin 109 which engages with a vertically elongated slot 110 formed in the slidable plate 36 to which the welt support is attached. The plate 36 being guided for horizontal motion by a key 111 held to the cam plate by the screws 112 and slidable in a groove formed in a block 113, is secured by the screws 114 to the welt support platen 22. Thus as the bracket 60 is moved rearwardly, the bell crank 102 is turned clockwise on its pivot as viewed in Fig. 6 and the welt support at the inside ball point is positioned for a large shoe, and movement of the bracket 60 forwardly for a small shoe also adjusts it inside the ball portion of the welt support for a small shoe.

Prior to placing a shoe in position upon the welt support, the handle 84 is pushed forward to lower the toe and heel supports as previously described.

40 The shoe is then placed on the welt support and pushed forward so that it engages in the welt crease of the shoe and shapes the welt support to the contour of the shoe around the forepart portions. The handle 84 is then pulled towards the operator, and the toe and heel supports are allowed to be moved upwardly by their springs 57 and 67 into contact with the shoe and last, as the rolls 75 follow the cams 85.

45 After the toe and heel supports contact the shoe and last rested upon the welt support, continued movement of the cam bar 80 by the handle 84 allows the rolls 87 to ride off the cam 86 into the depressions 115 thus allowing either the pawls 69 or 70 to engage in the ratchet teeth and to lock the heel and toe support posts 54 and 64 from downward movement.

50 Referring to Fig. 9, simultaneously with the release of the toe and heel supports and their movement to shoe contacting position, a cam 116 on the cam bar 80 contacts a roll 117 secured by the pin 118 to the bifurcated ends 119 of a rod 120 which is slidably mounted in a bearing formed in the support 95. The outer end of the rod 120 has a pin 121 which engages in an elongated slot 122 in the forked end of a lever 123, which is pivoted at 124 to a bracket 125 secured to the welt support platen 22 by the screws 126.

55 A lever 127, forked at one end to form the legs 128 and 129, is also pivoted at 124 to the bracket 125 and is connected to the lever 123 by a spring 130 so that it partakes of movement of the lever 123 and yet is able to yield under the influence of the spring 130, the tension of which may be adjusted by the screw 131. The upper end of the lever 127 is provided with a pin 132 which en-

gages in a vertically elongated slot formed in the head of a clevis 133, which is secured by means of a set screw to a shaft 134 slidably in a bushing 135, held by screws to the side of the welt support platen 22. The other end of the shaft 134 has formed thereon a clevis 136, and a formed block 137 having an outside contour 138, shaped to the outside shank contour of a shoe, is pivoted to the clevis 136 by the pin 139. The contour of the block 138 engages with the ends of the welt support fingers 30 so that pressing of the block 137 against the welt support will shape it and press it into engagement with the welt crease of the shoe.

When the cam bar 80 is returned to its former position to release the toe and heel supports from engagement with the shoe, the block 137 is also released from pressing engagement with the welt support fingers by means of a spring 142 which is held in a bore in the support 95 and which serves to bias the rod 120 and the levers 123 and 127 to their positions as shown by Fig. 10.

Fig. 9 shows the position of the levers 123 and 127 after movement has been imparted thereto, by the cam 116. As the welt support 26 is urged into the welt crease at the outside shank portion of the shoe under the pressure of the spring 130, a block 140, secured by the screws 141 to the last contacting member 56, engages the side of the cone of the last to prevent misplacement of the last by the pressure of the welt support.

Means for pressing the sole upon the shoe held by the welt support and the shoe and last contacting members, comprises a pad 150 of rubber or other resilient material having its sole engaging surface 151 shaped to the approximate contour of the shoe bottom. This pad is secured by the screws 152 to a plate 153 which is slidably mounted in grooves formed in blocks 154 which are secured by bolts 155 to a beam 156 which spans laterally across the press. A hand knob 157 is secured to the plate which carries the sole pressing pad, so that the plate with its pad can be moved from a position remote from the operators vision into a sole pressing position which is defined by stops 158 which engage with the edge 159 of the plate as it is pulled into sole pressing position.

The beam 156 is clamped by the nuts 161 to the rods 160 which are slidably mounted in bosses 162 and 163 formed on the press base 15 and the welt support platen 22. A beam 164 is secured by the nuts 165 to the lower end of the rods 160 and a fluid operated cylinder 166 is secured to the underside of the press base 15 by means of the bolts 167. The cylinder piston 168 is adapted to contact a boss 169 formed on the beam 164 so that admittance of a fluid under pressure to the cylinder 166 via the conduit 170 forces its piston 168 downwardly and consequently the upper beam 156, which carries the pressure pad 150 into pressing relation with the shoe bottom.

The collars 171 which surround the rods 160 are secured to the press base by the screws 172 and the springs 173, which surround the rods 160 fit into the bores of the collars and are secured thereto by the set screws 174. The other ends of the springs 173 fit within bores of the collars 175 threaded to the rods 160, and are secured thereto by the set screws 176. The springs return the beam 156 and the shoe pressing pad 150 to their uppermost position after the fluid is released from the cylinder 166.

Any conventional form of valve may be used to control the inlet and outlet of fluid to the

cylinder 166 and of course other arrangements such as an inflatable sole pressing pad could be used without departing from the spirit of the invention.

In the operation of the press described as viewed in Fig. 1 the sole pressing pad is moved to its rearward position by means of the hand knob 157. The handle 84 is also pushed rearwardly to release the pawls 69 and 70 and to lower the toe and heel supports 56 and 66.

The hand wheel 43 is then indexed to select the correct welt support length; to space the toe and heel supports 56 and 66, and to set the welt support half line width. The shoe is then placed upon the welt support 26 and pushed forwardly so that its welt crease engages the welt support and shapes it accordingly. The shoe is held in this position and the handle 84 is then pulled towards the operator to allow the heel and toe supports 56 and 66 to move upwardly and contact the shoe and last; to release the pawls 69 and 70 to lock the heel and toe supports from downward movement and to press the welt support into and shape it to the welt crease of the shoe at the outside shank portion.

Fluid is then admitted into the cylinder 166 and the pressure pad is thereby brought into pressing relation with the shoe bottom.

It is understood that any type of adhesive may be used to attach the sole to the shoe and that the press described can be used for other operations upon shoes wherein it is necessary to support the welt and/or sole extension.

Since certain changes may be made in the above construction and different embodiments of the invention could be made without departing from the scope thereof, it is intended that all matter contained in the above description or shown in the accompanying drawings shall be interpreted as illustrative and not in a limiting sense.

It is also understood that the following claims are intended to cover all of the generic and specific features of the invention herein described, and all statements of the scope of the invention, which, as a matter of language, might be said to fall therebetween.

Having described my invention, what I claim as new and desire to secure by Letters Patent, is:

1. A welt support comprising a plurality of finger like members each having one end thereof shaped to enter the welt crease of a shoe, and means forming a resilient covering for the shaped ends of said members connected to all of said members.

2. A welt support comprising a plurality of finger like members each having one end thereof shaped to enter the welt crease of a shoe, means in said members forming an anchorage, and a continuous strip of flexible material anchored to each of said members.

3. A welt support comprising a plurality of finger like members each having one end thereof shaped to enter the welt crease of a shoe, and a continuous strip of flexible and resilient material moulded to the shaped ends of said members.

4. A welt support comprising a plurality of finger like members, and a continuous strip of flexible and resilient material shaped to enter the welt crease of a shoe secured at one end of each of said members.

5. A welt support comprising a plurality of rigid finger like members each having one end thereof shaped to enter the welt crease of a

shoe, a continuous strip of flexible and resilient material shaped to enter the welt crease of the shoe, and means anchoring said strip to the shaped ends of said members.

6. A welt support comprising a plurality of rigid finger like members of substantially rectangular cross section and each having one end thereof shaped to enter the welt crease of a shoe, a strip of flexible and resilient material having an internal shape complementary to the shaped ends of said members and an external shape suitable for entry into the welt crease of the shoe, and means securing said strip to the shaped ends of said members.

7. A welt support adapted to at least partially surround a shoe and enter its welt crease, comprising a plurality of rigid finger like members of various lengths, a continuous strip of flexible material shaped to enter the welt crease of the shoe, and means securing said strip to one end of each of said members.

8. A welt support comprising a plurality of finger like members of substantially rectangular cross section arranged in a substantially horizontal plane and each having one end thereof shaped to enter the welt crease of a shoe, and a continuous strip of resilient material connected to the shaped end of each of said members whereby said assembly can be flexed in more than one plane to assume the contour of a shoe.

9. In a device for operating upon shoes, the combination comprising a flexible welt support upon which a shoe may be positioned, means for flexing said support in two planes substantially to conform it to the contour of the welt crease of the shoe, and means for rigidly retaining said support in its flexed position to resist vertically applied pressure.

10. In a device for operating upon shoes, the combination of a flexible welt support for engagement with the welt of a shoe, said support having one end terminating at a point corresponding substantially to the ball point of the shoe and having its other end extending beyond the space defining the heel end of the shoe, means securing said one end of said support against movement longitudinally of the shoe, means including a rotary member connected to said other end of said support for varying its effective length and contour, means including a hand operated member for rotating said member, and means for indicating to an operator the proper positions of said hand operated member for different sizes of shoes.

11. In a device for operating upon shoes, the combination comprising a flexible welt support for engagement with the welt of a shoe, means securing one end of said support against movement longitudinally of the shoe, means including a rotary member connected to the other end of said support for varying its effective length and contour, means including a hand operated member for rotating said member, and means for indicating to an operator the proper positions of said hand operated member for different sizes of shoes.

12. A device for operating upon shoes comprising a flexible welt support strip shaped to conform with at least the contour of the forepart of a shoe, a plurality of finger like members attached at their inner ends to said strip, and a plate having an opening shaped to conform substantially with said contour and having a wall around said opening under and in contact with said members for restraining down movement thereof.

13. A device for operating upon shoes comprising a flexible welt support strip shaped to conform with at least the contour of the forepart of a shoe, a plurality of finger like members having their lower surfaces arrayed in substantially a horizontal plane, attached at their inner ends to said strip, and a plate having an opening shaped to conform substantially with said contour and having a wall around said opening with a substantially horizontal upper surface in contact with said fingers for restraining down movement thereof.

14. A device for operating upon shoes comprising a flexible welt support including a strip shaped to conform with at least the contour of the forepart of a shoe and a plurality of spaced finger like members attached at their inner ends to said strip, a plate having an opening shaped to conform substantially with said contour and having a wall around said opening under and in contact with said members for restraining down movement thereof, said plate having a recess formed in said wall under the outer ends of said members, means for moving said support inwardly, and pins attached to said outer ends and extending below same into said recess for limiting, by contact with the inner wall of said recess, the inward movement of said support.

15. A device for operating upon shoes comprising a flexible welt support including a strip shaped to conform with at least the contour of the forepart of a shoe and a plurality of spaced finger like members attached at their inner ends to said strip, means for moving said support inwardly, and means for limiting the inward movement of said support.

16. A device for operating upon shoes comprising a flexible welt support including a strip shaped to conform with at least the contour of the forepart of a shoe and a plurality of spaced finger like members attached at their inner ends to said strip, means for moving said support inwardly, and means including said members for limiting the inward movement of said support.

17. A device for operating upon shoes comprising a flexible welt support including a strip shaped to conform with at least the contour of the forepart of a shoe and a plurality of finger like members attached at their inner ends to said strip, a plate having an opening shaped to conform substantially with said contour and having a wall around said opening under and in contact with said members for restraining down movement thereof, and means for moving said support inwardly, said members in the toe portion of said support being longer than the others of said members whereby upon extreme inward movement of said support said longer members remain in contact with said wall.

18. In a device for operating upon shoes, the combination of a flexible welt support for engagement with the welt of a shoe, means restraining one end of said support against movement longitudinally by a shoe, and means including means attached to the other end of said support for varying its effective length and contour and including means connected to said restraining means for adjusting the position of same.

19. In a device for operating upon shoes, the combination of a flexible welt support for engagement with the welt of a shoe, a toe support for the shoe, and interconnected means for simultaneously varying the effective length and contour of said welt support and the position of said toe support.

the point corresponding to the heel end of the shoe, means for supporting said one end against longitudinal movement by the shoe, means including a rotary member for winding up said other end of said support for varying its effective length and contour, interconnected means for rotating said member and for adjusting the position of said supporting means for receiving different sizes of shoes, hand operated means for actuating said interconnected means, and means for indicating to an operator the correct positions of said hand operated means for different sizes of shoes.

33. In a device for operating upon shoes, the combination of a flexible welt support for engagement with the welt of a shoe, said support having one end terminating at a point corresponding substantially to the ball point of the shoe and having its other end extending beyond the point corresponding to the heel end of the shoe, means for supporting said one end against longitudinal movement by the shoe, a toe support for the shoe, means including a rotary member for winding up said other end of said support for varying its effective length and contour, means including interconnected means for rotating said member, for varying the position of said supporting means and for varying the position of said toe support, hand operated means for actuating said interconnected means, and means for indicating to an operator the correct positions of said hand operated means for different sizes of shoes.

34. In a device for operating upon shoes, the combination of a flexible welt support upon which a shoe may be positioned, said support being shaped to have inner edges fit into the welt crease of the shoe, means forming a supporting surface under the outer portions of said support for restraining down movement of the shoe, means anchoring the ends of said support, and means including means for pressing inwardly upon outer edges of said support for forcing said inner edges into said crease.

35. In a device for pressing the bottoms of shoes mounted upon lasts, the combination of a flexible welt support upon which a shoe may be positioned, said support being shaped to have inner edges fit into the welt crease of the shoe, means forming a supporting surface under the outer portion of said support for restraining down movement of the shoe, means including means for pressing inwardly upon outer edges of said support for forcing said inner edges into said crease, means for supporting the shoe and its last at the forepart and the heel thereof for the pressing operation, means for positioning said

supporting means against the shoe and its last, and means including interconnected means for first actuating said positioning means for supporting the shoe for the pressing operation and for then actuating said pressing means for pressing said inner edges of said support into said crease.

36. In a device for pressing the bottoms of shoes mounted upon lasts, the combination of a flexible welt support upon which a shoe may be positioned, said support being shaped to have inner edges fit into the welt crease of the shoe, means for adjusting said support for a particular size of shoe and for then anchoring the two ends of said support against movement, means forming a supporting surface under the outer portions of said support for restraining down movement of the shoe, means including means for pressing inwardly upon outer edges of said support between said ends for forcing said inner edges into said crease, means for supporting the shoe and its last at the forepart and the heel thereof for the pressing operation, means for positioning said supporting means against the shoe and its last and for then locking same into position, and means including interconnected means for first actuating said positioning means for supporting the shoe for the pressing operation and for then actuating said pressing means for pressing said inner edges of said support into said crease.

37. In a device for pressing the bottoms of shoes mounted upon lasts, the combination of a flexible welt support upon which a shoe may be positioned, said support comprising a plurality of spaced finger-like members having their inner edges shaped to enter the welt crease of the shoe, a strip of flexible material interconnecting said member, means for adjusting said support for a particular size of shoe and for then anchoring its two ends against movement, means forming a surface under the outer portions said members for restraining down movement of the shoe, means for pressing inwardly against the outer ends of members of said plurality between said ends for pressing said inner edges into said crease, means for supporting the shoe and its last at the forepart and the heel thereof for the pressing operation, means for positioning said supporting means against the shoe and its last and for then locking same into position, and means including interconnected means for first actuating said positioning means for supporting the shoe for the pressing operation and for then actuating said pressing means for pressing said inner edges of said support into said crease.

WILLIAM CARPENTER CARD, JR.
